BLOCK ALIGNER

John L. Pagona, 19 Lincoln Ave., North Irwin, Pa.
Filed Aug. 19, 1960, Ser. No. 50,708
1 Claim. (Cl. 33—85)

This invention relates to line holders and the like, and more particularly to an improved adjustable line holder for holding and positioning a mason's line in an offset relationship to align and facilitate the laying-up of different size building block, brick, etc.

Various aligners have been proposed in the past for attaching a mason's line to block and the like so that additional courses may be laid-up; however, none of these devices have adequately set forth a provision for stepping-off or offsetting selected portions of a course, such as with different sized block or brick. With known devices, it is necessary to first align the block of one size, and after completing the laying-up of block of that size, to then re-align to complete the course with the block of a different size.

A further disadvantage which accompanies the known type of block aligners is that they do not hold and maintain the line directly along the edge of the block to be laid-up, but are raised or offset from the edge as much as an eighth to a quarter of an inch, which results in appreciable error over the extent of numerous courses comprising a wall structure.

A further disadvantage is encountered with known line holders when constructing offset courses in an excavation. In such a situation, due to limited space between the wall of the excavation and the construction, it is necessary for the mason to work from the inside of the construction. Since the inside surface of the construction is usually the planar surface, with the outside surface providing the offset, known line holders must be aligned along the planar inside surface of the construction. As a result, it is necessary for the mason to lift the block up and over the line to place it in position on the other side of the line. Such excess lifting is extremely fatiguing and materially lowers the mason's efficiency.

It thus has been an object of my invention to solve the above-mentioned problems heretofore presented in the mason construction art;

An additional object of my invention has been to provide an improved block aligner for holding and positioning of a mason's line in a pre-determined offset relationship to align blocks of different widths within a single course;

A further object of my invention has been to provide an easily adjustable block aligner which is easily portable and economical to manufacture;

A still further object of my invention has been to provide a block aligner which retains an alignment line in contact with an edge of the blocks which are laid-up within the course upon which the aligner is applied.

An additional object of my invention has been to provide an improved block aligner which, upon a single setting, may retain a line in a stepped relationship along the staggered edge of an offset course and opposite the side from which the block are laid-up to align the full extent of the course;

These and other objects of my invention will be apparent to those skilled in the art from the following disclosure and accompanying drawings in which:

FIGURE 1 is a perspective view of a preferred embodiment of my block aligner;

FIGURE 2 is a side view in elevation of the device shown in FIGURE 1;

FIGURE 3 is a sectional view in elevation taken trans-

2

versely through the adjustment slot with the adjustable slide in a backward position; and,

FIGURE 4 is a perspective view illustrating the positioning of the block aligner on a block of one width for lining up blocks of that width along one direction and blocks of a smaller width along an opposite direction.

Referring now to the drawings, the block aligner 10 comprises a carrier bar 11, a slide bar 12, and an end frame 13. The slide bar 12 is slidably retained on the carrier bar 11 by suitable means, such as countersunk screws 15 and wing nuts 17. The screws 15 extend upwardly through countersunk bores 16, formed within the slide bar 12, and through a longitudinally-extending adjustment slot 14, formed in the carrier bar 11. Wing nuts 17 are threadable on the screws 15 and serve to adjustably secure the slide bar 12 in a pre-determined position on the carrier bar 11.

The slide bar 12 extends transversely-outwardly a greater distance than the transverse extent of the carrier bar 11, and is provided with a plurality of bores 18, which as shown, may be transversely aligned and positioned adjacent the outer edges of the carrier bar 11. A pin 19 extends downwardly through each of the bores 18 for guiding an alignment string or line S. The pins 19 may be retained within the bores 18 by any suitable means such as a friction fit or screw fit. Also, broad headed nails may form the pins 19, and when positioned downwardly through the bores 18, they are held in place by the overlapping carrier bar 11.

The slide bar 12 is provided with an aligning forward flange member 20 having a rear surface 21 which is in alignment with a forward pair of the line positioning pins 19. As shown in the drawings, the forward flange 20 may be welded, such as at w, to an under portion of the slide bar 12.

The end flange 13 is of an L-shape and has an upper or horizontal portion 22 which is adapted to rest upon an upper surface of a block or the like, and a lower or vertical portion 23 which is adapted to be aligned against a side edge portion of such a block. As shown in the drawings, the end flange 13 is secured to the carrier bar 11 by any suitable means, such as a weld w.

The slide bar 12 is provided with an indicator mark 24 which is positioned in transverse alignment with the forward pins 19 and the rear surface 21 of the forward flange 20. A plurality of position marks 25 are provided on the carrier bar 11, and may represent setting positions for such standard size blocks as the 8", 10", and 12" block.

In building construction it frequently becomes necessary to provide selective courses with an offset. For instance, when it is desired to brick a structure to grade in hilly terrain, two different sized block are required to be laid-up in a single course, so as to facilitate the placement of brick along that portion of the course which will be above ground level. The front and rear pins 19 of slide bar 12 are spaced-apart a distance equal to the width of a normal brick. Therefore, as shown in FIGURE 4, the slide bar 12 may be positioned on the carrier bar 11 to fit over the main block B and a line S is stretched from a line block or corner block (not shown) across a forward pin 19 on one side of the slide bar and diagonally-backwardly across a rearward pin 19 on the opposite side of the slide bar to another corner block on the opposite end of the line.

When so positioned, the line S laying outwardly away from the left-hand side of the block aligner, shown in FIGURE 4, will adequately align the main sized block B along that extent, while the line S extending outwardly to the right of the block aligner is offset from the outer edge of the block B a distance approximately equal to the average width of a brick so that the smaller block b

may be adequately and conveniently aligned along the right-hand extent. When the block aligner 10 is positioned upon the block B, the rearward pins 19 will project downwardly within the openings, recesses or holes h which are usually formed in such blocks.

It thus can be seen that my block aligner eliminates the necessity of providing two separate and distinct alignments along a single course where it is desired to lay-up blocks of two different widths, such as where it is desired to brick the grade and the grade runs along a portion of that course. Further, since the line S is retained along the edge of the offset side of the block (which may be along the outside of the construction and adjacent the wall of an excavation), it is possible for a mason to work from the inside of the construction without interference with the line. The block aligner 10 is preferably made of aluminum, so as not only to be of light weight for ease in portability, but also is thereby of a sturdy, durable and rugged construction.

Although I have set forth my now preferred embodiment, it is understood that various changes and modifications may be made thereto without departing from the spirit and scope of my invention as defined in the appended claim.

I claim:

An improved block aligner for use with blocks having

vertically-extending recesses therein, for off-settably retaining a mason's line so that blocks of two different widths may be laid-up along the same course of a single wall portion with only one alignment operation comprising, a longitudinally-extending carrier bar having an end flange secured thereto for alignment along one edge of a block that is parallel to the course, a slide bar slidably carried by said carrier bar for desired longitudinal adjustment thereon, a forward end flange secured to an under surface of said slide bar for alignment with an opposite edge of the block to thus determine the longitudinal positioning of said slide bar on said carrier bar, means for securing said slide bar in such pre-determined position on said carrier bar, and at least four pins mounted in longitudinally-spaced pairs on and extending downwardly from said slide bar, one of said pairs of pins being substantially aligned with said forward end flange.
